UNITED STATES PATENT OFFICE.

JOHN SHARP AND WILLIAM SHARP, OF CLEVELAND, OHIO.

AEROPLANE.

1,177,656.

Specification of Letters Patent.

Patented Apr. 4, 1916.

Application filed June 30, 1911. Serial No. 636,275.

To all whom it may concern:

Be it known that we, JOHN SHARP and WILLIAM SHARP, citizens of the United States, and residents of Cleveland, in the county of Cuyahoga and State of Ohio, have invented certain new and useful Improvements in Aeroplanes, of which we hereby declare the following to be a full, clear, and exact description, such as will enable others skilled in the art to which it appertains to make and use the same.

The objects of the invention are to provide a self propelling aeroplane preferably of the monoplane type in which are provided improved devices for obtaining stability of the machine under conditions of air currents varying in intensity of pressure and changeable in direction, and also to provide steering, elevating, and depressing devices of great simplicity in construction and efficiency and practicability in use.

The invention also has reference to automatically acting means for adjusting the balancing devices which are operatively connected with the seat of the driver whereby the weight of the driver will place the machine in equilibrium as it is automatically shifted, by variations in the angular position of the machine in the air and the effort of the driver to maintain his position will operate the balancing mechanism.

Other features of the invention comprise the construction of the frame with trussed supports in lieu of stay wires, which rigidly secure the planes and also comprise the specific character and construction of the operating mechanism for the balancing and lifting and depressing planes and steering devices, and the corrugated or transversely 40 and closely veined or ribbed main and floating planes and propeller, whereby a more intimate engagement with the air can be effected, to prevent slipping or sliding therein.

45 The invention further comprises the combination and arrangement of parts and construction of details hereinafter described, shown in the accompanying drawings and specifically pointed out in the claims.

50 In the accompanying drawings Figure 1 is a plan view of the aeroplane; Fig. 2 is a side elevation thereof; Fig. 3 is a front

elevation thereof; Fig. 4 is a longitudinal section through the steering head showing the devices operatively connected with the steering head for moving the steering planes, balancing planes, and elevating and depressing planes; Fig. 5 is a transverse section on line *a*—*a* Fig. 4; Fig. 6 is a longitudinal horizontal central section of the steering head; Fig. 7 is a transverse section of a portion of the main supporting plane showing the corrugated arrangement thereof; Fig. 8 is a transverse section of one of the planes; showing ribbed construction of wood and silk; Fig. 9 is a longitudinal section of a plane formed of wood and silk; Fig. 10 is a front elevation showing the main plane composed entirely of pivoted balancing planes; Fig. 11 is a side elevation of one of the wheels and bearing therefor for use on land; Fig. 11^a is a front elevation thereof; Fig. 12 is a transverse section of the diamond frame showing a seat for the operator depending from the bridge and operating means for the several steering and balancing devices operatively connected with the seat support; Fig. 12^a is an enlarged perspective view of the controlling mechanism; Fig. 13 is a plan view of the corrugated propeller; Fig. 14 is a side elevation thereof; Fig. 15 is a front elevation of a modified form in which two main supporting planes are crossed to provide greater area of supporting surface; Fig. 16 is a front elevation showing a trussed form of wing or main plane; Fig. 17 is a side view of a trussed inner end; Fig. 18 is a side view of a trussed outer end; Fig. 19 is a side elevation of a portion of the front end of the frame showing location of engine and of the plane which controls the angle of flying when descending or rising; Fig. 20 is a perspective view of an aeroplane embodying our invention.

In these views a triangular frame composed of side bars 1, 1 and lower central bar 2 connected by struts 2', 2'', forms the body of the aeroplane upon which all the parts are secured. This body tapers from the front to the rear and the motive power such as a gasoline engine 3 is mounted upon the front portion thereof in front of the driver who is seated in a central position between

the side bars and preferably on the lower bar at 4.

5 is the propeller situated in front of the frame on the engine shaft 6. 7, 7 are the main supporting planes which are inclined upwardly and forwardly and have preferably a slight curvature underneath to give a constant tendency to elevate the front end of the frame. Their rear ends are preferably extended below the driver seat as shown in Fig. 2. These planes are mounted on laterally extending rods L, L' rigidly secured to the upper bars 1, 1. These planes extend laterally on each side of the frame and preferably are separated to leave the aeroplane open on the longitudinal center thus giving the operator a free view above the supporting planes in all directions, and rendering the danger of collision less imminent and giving the driver opportunity for perfect control of the aeroplane while giving a low point of center of gravity for his seat.

The main supporting planes may be rigidly secured by means of tension or stay wires 8, 8, and 9, 9 attached to an elevated central bridge 10, which extends over the planes and driver's seat, and with its brace bars 11, 11 forms with the triangular body 30 a diamond shaped front portion of great rigidity and lightness of construction.

The rear edges of the front planes widen as they approach the frame, having relatively narrower outer tips 12, 12 to which the stay wires 8, 8 and 9, 9 are attached. A laterally extending rigid rear or floating plane 13 is horizontally attached to the rear of the frame and is also preferably inclined to give a lifting impulse to the rear of the frame. It is supported by transverse bars 14, 14 and is also closely and transversely ribbed or corrugated to aid in effecting frictional engagement with the air and to prevent slipping.

45 Two directing rudders 15, 15 are shown at the rear of the machine pivoted on posts 16, 16 mounted on one of the bars 14 and connected together at their rear edges so as to move in unison. The position of these 50 rudders underneath the horizontal keel plate 13 enables the air to have immediate effect thereon as it passes underneath this plate. A plane or planes 17, 17 hinged to the rear of the rear floating vane 13 serve 55 for elevating or depressing the aeroplane without causing sudden soaring or diving and the consequent loss of balance of the machine which is apt to be occasioned by attaching the elevating and depressing 60 planes to the front part of the machine. By attaching these planes to the rear extremity however the rear portion can rise and fall without immediately changing the position of the front end of the driver and

thereby increasing the possibilities of control.

The equilibrium of the aeroplane is maintained by means of tilting longitudinally placed narrow planes 19, 19 which may be pivoted only in the extreme outer edges of 70 the main supporting planes as shown in Figs. 1 and 3, or may compose the entire supporting surface of the planes as shown in Fig. 10.

The planes by means of which the direction, elevation, depression and equilibrium of the machine are controlled are operable by the driver while seated in the frame and are connected preferably as shown with a common steering post P accessible to the 80 hands of the driver.

The rudder planes 15 are operated by means of cords or wires W, W which pass through suitable eyes E, E on the frame and are attached to the ends of swinging 85 arms A, A upon a central rod R in the post P so that by turning a hand wheel H the driver can readily direct the movements of the aeroplane. The elevating and depressing plane is connected by means of wires F', F' with the horizontal sliding bar B, which is movable vertically up and down in guides B', B' upon a plate B², secured in the frame in front of the driver. The bar can be raised or lowered by raising 95 or lowering the front extremity or toe T of the steering post, which engages a slot 50 in the bar B. For this purpose the steering post is mounted in a pivotal or universal bearing Z which permits of movement in two directions and the operator can elevate or depress the front end of the post at will, to adjust the position of the elevating and depressing plane.

The pivoted or tilting planes by means of 105 which the equilibrium of the machine is controlled are connected by means of wires X, X to a vertical bar V crossing the bar B at right angles. This bar V is slotted at V' and the toe T passes also through the 110 slot V' and when laterally moved will operate the balancing planes just as described. To make this movement an automatic one in which the members B and V can be moved by the action of the body of 115 the operator, the seat 4 is suspended by means of a hanger J' and a universal pivotal bearing J secured intermediate of the upper bar 10 and lower bar 2 of the frame, so that the body will swing freely. 120

To the upper end of the hanger is attached a projection or toe J² similar to the projection T upon the post P shown in Fig. 6, which acts in a similar manner upon crossed bars B³ and B⁴ overhead, which are 124 also similarly slotted so that the toe will extend through both of them at the crossing point. These bars are respectively con-

nected with the balancing vanes and elevating and depressing planes to operate them. The steering wheel H is then employed only for operating the rudder.

5 In Figs. 13 and 14 the corrugated construction of the propeller blade is shown, whereby a more lingering contact with the air is obtained. In Fig. 10 the planes by means of which the aeroplane is supported 10 in the air are shown separated into a series of sections or smaller planes 19', pivoted for angular adjustment in the side bars of the main plane. These smaller planes are attached together and are simultaneously 15 operated so that while the planes on one side of the central frame are closing those on the other side are opening, thus affording immediate relief from sudden pressure or gusts of wind and enabling the operator to 20 keep the machine in equilibrium, with little effort. The planes shown in this figure differ in no particular from the pivoted planes shown in Fig. 3 at the outer ends of the main planes, but are greater in number 25 to obtain a quicker effect.

In Fig. 15 an aeroplane is shown where the supporting surface of the main planes 7', 7' is substantially doubled by crossing two of them, which are secured by wires 30 51 connecting their outer ends and stay wires 8 and 9. This construction greatly increases the buoyancy of the aeroplane.

In Figs. 11 and 11^a are shown a shock absorbing device for the running wheels 35 upon which the aeroplane is supported when it alights. This device is simple and efficient and comprises the brackets O, each having a cylindrical vertical sleeve O' attached thereto in which is mounted rod O² 40 through which and through slots O³ in the sleeves O', O', passes the shaft O⁶ upon which the wheel O⁴ is mounted. Springs O⁵ give resiliency to the shaft when the weight of the aeroplane bears thereon.

45 In Figs. 16, 17 and 18 are shown planes provided with triangular trusses which support them rigidly, and no guy wires are necessary although they can be used for greater safety if desired to connect the bridge and 50 upper edge. In these views rods C are connected with the rods M and L by means of struts D, D, thus forming a triangular tapering truss able to support itself rigidly. The wires N, N strengthen the outer edges 55 L but add no support to the truss. A guy 8 can be employed but under ordinary circumstances will not be necessary.

In Fig. 19 is shown a small plane K operated by means of a rock arm K' which 60 serves to direct the movement in starting or stopping the machine since the movement is easily controlled at the front of the machine. This small plane is pivoted between the side bars of the frame in front of

the same, and can be controlled by any convenient means accessible to the operator. 65

Having described the invention what we claim as new and desire to secure by Letters Patent is:

1. In an aeroplane, a main frame, main 70 horizontally extending planes secured to said frame at the front of the machine, balancing vanes pivoted in said main planes, an elevating and depressing vane pivoted at the rear of the frame, a support within 75 said frame, longitudinally slotted vertical and horizontal bars slidably movable upon said support at right angles to each other in respectively vertical and horizontal directions, flexible connections between said vertical bar and said balancing vanes, flexible connections between said horizontal bar and said elevating and depressing vane, an operating lever for both said bars, 80 said lever provided with a projection entering and slidably movable in the slots in said bars, a vertical rudder and connections between said lever and said rudder adapted to operate the rudder when the lever is turned on its longitudinal axis and adapted 85 to also to operate the rudder to some extent when the lever is moved about a transverse axis to operate the balancing planes. 90

2. In an aeroplane, a main frame, main 95 lateral planes secured to the front of the frame, pivoted balancing vanes therein, a horizontal elevating and depressing vane pivoted in the rear of said frame, a vertical rudder pivoted in the rear of said frame and an operating device for said vanes and 100 rudder comprising a support transversely secured in said frame, vertically and horizontally movable members sliding upon said support, said members being longitudinally slotted, a steering post, arms carried from 105 said post, an extension of said post passing through the slots in both said sliding members, a support in said frame intermediate of the ends of said post, in which support said steering post has universal movement, 110 and flexible connections between said horizontally sliding member and said balancing vanes and between said elevating and depressing vane and said vertically movable member, and between said arms and said 115 rudder, said connections being adapted to operate the rudder and the balancing vanes simultaneously.

3. The combination with the frame and laterally extending main planes, pivoted 120 balancing vanes in said main planes, an elevating and depressing vane and a rudder, of a support in said frame, a post having a universal movement in said support, slotted and crossing members engaged at 125 their crossing point by said post, and operated thereby, one member slidably movable at right angles to the other member,

said members respectively and operatively connected with said vanes, mechanism rotatable upon said post for operating said rudder, the arrangement being such that the rudder may be operated independently of the balancing vanes, but is operated to some extent upon operation of the balancing vanes.

In testimony whereof, we hereunto set our hands this 8th day of October, 1910.

JOHN SHARP.
WILLIAM SHARP.
